Primary Examiner — Susan Moon Lee(74) *Attorney, Agent, or Firm* — ScienBiziP, P.C.(57) **CLAIM**

The ornamental design for a disposable pet waste collector, as shown and described.

DESCRIPTION

FIG. 1 is a first perspective view of a disposable pet waste collector showing my new design;

FIG. 2 is a second perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 shows the disposable pet waste collector in an in-use configuration; and,

FIG. 10 is an exploded perspective view of the disposable pet waste collector in which the disposable pet waste collector is in a disassembled condition.
